UNITED STATES PATENT OFFICE.

SAMUEL JAMES, OF FERNWOOD, ASSIGNOR TO HIMSELF, THOMAS V. COOPER, OF MEDIA, AND GEORGE A. FRAME, OF WEST CHESTER, PENNSYLVANIA.

DESIGN FOR A BADGE.

SPECIFICATION forming part of Design No. 15,307, dated August 19, 1884.

Application filed July 3, 1884. Term of patent 3½ years.

To all whom it may concern:

Be it known that I, SAMUEL JAMES, a citizen of the United States, and a resident of Fernwood, Delaware county, Pennsylvania, have invented or produced a new and original Design for a Badge, of which the following is a specification.

My design is fully shown in the accompanying drawing, and comprises the conventional representation of a pine-cone, *a*, a number of pine-twigs, *b*, and a corps-mark, *d*, consisting of a square plate, in which is a tablet of the shape of a cartridge-box.

I make no claim to the mark *d*, considered separately, but only in connection with the pine-cone or pine cone and twigs, the latter being the novel element in the design.

I claim—

1. The design for a badge, said design con-

sisting of the conventional representation of a pine cone and twigs, substantially as shown and described.

2. The design for a badge, said design consisting of the conventional representation of a pine-cone and rectangular corps-mark, *d*, with beaded edge, substantially as shown and described.

3. The design for a badge, said design consisting of the representation of a corps-mark, a pine-cone, and pine-twigs, all substantially as shown and described.

In testimony whereof I have signed my name to this specification in the presence of two subscribing witnesses.

SAML. JAMES.

Witnesses:

JAMES F. TOBIN,
HARRY SMITH.
